(57) **CLAIM**

The ornamental design for a beverage can tab, as shown and described.

DESCRIPTION

FIG. 1 is a top plan view of a beverage can tab according to a first embodiment of my new design;

FIG. 2 is a top perspective view thereof;

FIG. 3 is a bottom plan view thereof;

FIG. 4 is a bottom perspective view thereof;

FIG. 5 is a front elevation view thereof;

FIG. 6 is a back elevation view thereof;

FIG. 7 is a right side elevation view thereof, a left side elevation view being a mirror image of the right side elevation view;

FIG. 8 is a top plan view of a beverage can tab according to a second embodiment of my new design;

FIG. 9 is a top perspective view thereof;

FIG. 10 is a bottom plan view thereof;

FIG. 11 is a bottom perspective view thereof;

FIG. 12 is a front elevation view thereof;

FIG. 13 is a back elevation view thereof; and,

FIG. 14 is a right side elevation view thereof, a left side elevation view being a mirror image of the right side elevation view.
